UNITED STATES PATENT OFFICE.

GEORGE H. MARSH AND HARRY E. BEDELL, OF PATERSON, NEW JERSEY.

CIGAR-CUTTER.

SPECIFICATION forming part of Letters Patent No. 253,301, dated February 7, 1882.

Application filed November 28, 1881. (No model.)

To all whom it may concern:

Be it known that we, GEORGE H. MARSH and HARRY E. BEDELL, citizens of the United States, residing at Paterson, Passaic county, 5 State of New Jersey, have invented a new and useful Improvement in Cigar-Cutters, of which the following is a specification, reference being had to the accompanying drawings, forming a part thereof.

10 Our invention relates to devices for cutting off the ends of cigars, and has for its object the production of a cigar-cutter of simple construction, which will more perfectly cut off the ends of cigars than any device now in use for that purpose.

15 Figure 1 is a perspective view of our newly-invented cutting device, showing the general arrangement of parts, with a cigar in position to be cut; and Fig. 2 is a section of the same, 20 showing the cutter, and how the same is held in position against the flange by a spring that is arranged internally.

a represents the bed of the device, which is made of metal, having a groove, a', formed in 25 the top of the same to accommodate the cigar to be operated on. The bed a is also provided with an opening in the top to keep in position a paste-cup, b, which greatly facilitates the operative in finishing his cigars, his paste-cup 30 being always in place. The bed is also provided with a standard, h, through which slides a gage, i, which can be adjusted to suit the various lengths of cigars indicated on the index-plate k. The head of the gage i slides in and 35 conforms to the shape of the groove a', by reason of which it never leaves its position in the groove while being adjusted to suit the different lengths of cigars, and is held to its adjusted position by a thumb-screw, g'. The device may 40 be held in a fixed position by screws inserted in the holes g'.

To the end of the bed-plate a there is secured by screws g a pedestal or frame, e, the rear side of which, where the cutter passes through, 45 is removable, being held in position by a screw, g', and may be removed, when desired, by unscrewing the same.

To the inner side of the removable plate e' there is arranged a spring, n, which is secured

to the plate by a screw, n', the spring n serving the double purpose of holding the cutter f' close to the guard and preventing it from wabbling, securing thereby undeviating motion to the cutter f'. It also holds the cutter f' in its elevated position.

55 It is found by those who use cigar-cutting devices that the oval and concave cutters are objectionable on account of their large bearing-surfaces on the cigars, which tend to press the cigar out of shape and tear the wrapper of the cigar while the same is being cut. The same objections are found to exist in the convex form of the cutters. They work imperfectly and damage the cigars on account of the pressure on the cigar by reason of the large bearing-surface thereon, whereas in our V-shaped cutter these objections are removed.

60 By a slight pressure of the hand of the operative on the hood c the cutter f' is depressed and brought in contact with the cigar f'', which 65 is in position to be cut in the groove a'. The cutters f f' begin to cut at the four corners or angles. Their cutting-edges being quite erect gives them a very small bearing-surface on the cigar. The cutting-edges cutting in the 70 direction of each other makes it impossible for the cigar f'' to leave its position in the angles of the cutting-edges until the cutting off of the end of the cigar is completed. The angular form of the cutting-edges of our newly-invented V-shaped cutter requires less power to 75 do the cutting than any cutter now in use, causing less pressure on the cigar, preventing damage thereby to the wrapper. The work of cutting being completed, the spring d, having 80 a slotted end that works against the flanges d', raises the cutter f to its elevated position, where it is held by the spring d, aided by spring n. The spring d is removable, the lower end 85 of it being held against the edge of the frame e by the bed-plate a projecting somewhat over the inner side of the frame e, which keeps the spring in position; but the spring may be removed, when desired, by raising the spring out of position at the bottom, having first pulled 90 the top from under the flanges d'. The hood c projects far enough over the flanges d' to keep 95 the hand of the operative from contact with the

spring when in the act of cutting. The lower cutter *f* is rigidly held to the end of the bed *a* by screws *g*, *g*.

Having thus described our invention, what we claim, and desire to secure by Letters Patent, is—

The combination of the V-shaped cutter *f'*, frame *e*, constructed with a removable plate, *e'*,

screw *g*⁴, spring *n*, spring *d*, flanges *d'*, hood *e*, screw *g*³, and bed-plate *a*, as shown, and for the purposes set forth.

GEORGE H. MARSH.
HARRY E. BEDELL.
